Application March 20, 1937, Serial No. 132,127

14 Claims. (Cl. 120—18)

This invention relates to mechanical lead pencils.

One of the objects of the invention is to provide a mechanical lead pencil adapted to store a plurality of leads which may be brought successively to writing position by novel lead projecting actuation.

A further object of the invention is to provide in a mechanical pencil projecting means which, upon reaching the extreme forward position of its travel, automatically returns to its extreme rear position.

A further object of the invention is to provide a lead magazine which can be inserted in loaded condition in the pencil and which includes means for positively moving the leads automatically and successively to ejecting position.

Further objects, advantages and capabilities of the invention will be apparent from the following description of preferred embodiments of the invention taken in conjunction with the accompanying drawings, in which

Fig. 1 is a longitudinal cross section of a pencil embodying the invention;

Fig. 2 is an exterior view of the barrel;

Fig. 3 is a perspective view of the clip;

Figs. 4 and 5 are perspective views of alternative types of thread followers;

Fig. 6 is an end view and side elevation of the lead ejector;

Fig. 7 is a side elevation of the spring which returns the lead ejector to the rearward extremity of its travel;

Fig. 7a is an end view thereof;

Figs. 8 and 9 are side elevations of the thread members;

Figs. 8a and 9a are corresponding end views thereof;

Figs. 10 and 11 are perspective views of the tip member;

Fig. 12 is a side elevation, partly in section, of the driving tube;

Fig. 13 is a longitudinal cross section of a further embodiment of the invention;

Figs. 14 and 15 are side elevations of the thread members of the pencil shown in Fig. 13;

Figs. 14a and 15a are corresponding end views thereof;

Fig. 16 is a side elevation, partly in section, of the driving tube of the pencil shown in Fig. 13;

Fig. 17 is an elevation of the abutment disk of the pencil shown in Fig. 13;

Fig. 17a is a sectional view thereof taken on the line 17a—17a of Fig. 17;

Fig. 18 is a perspective view, partly broken away, of a magazine for the leads;

Fig. 18a is a perspective view of a closure member therefor;

Figs. 19 and 20 are perspective views of alternative types of springs for the magazine;

Figs. 21, 22 and 23 are end views of the magazine with different numbers of leads therein;

Fig. 24 is a perspective view, partly broken away, of another magazine for the leads;

Fig. 25 is a fragmentary side elevation of a spring for the magazine shown in Fig. 24;

Fig. 25a is an end elevation thereof; and

Figs. 26, 27 and 28 are end views of the magazine shown in Fig. 24 with different numbers of leads therein.

In the pencil shown in Fig. 1 there are three principal elements, namely, the tip member 1, the magazine M and the lead ejecting means.

The tip member 1 frictionally grips the lead 20 therein and prevents it from sliding out of the pencil. As shown in Fig. 10, the wall at the lower end of the tip member is relatively thin and formed in the shape of a triangle. The triangle is of such size that when a lead is pushed through 25 the tip member, the sides of the triangle are bowed outwardly as shown in Fig. 11. This results in a pressure being exerted by the sides of the triangle upon the lead and causes the lead to be frictionally gripped by the tip member. 30

The upper portion 2 of the tip member is cylindrical and is frictionally held in a corresponding recess in closure member 3. The latter tapers smoothly from the tip member to the cylindrical barrel 4 and has a cylindrical upper 35 portion 5 which is frictionally and removably held in the lower end portion of cylindrical driving tube 6 which is rotatably mounted in the barrel 4. Grooves 7 (see Fig. 12) are provided in tube 6 to prevent relative rotation between the tube and closure member 3.

Within approximately the lower half of tube 6 is magazine M which is adapted to be removed from the tube upon the removal of closure member 3 from the tube. A detailed description of the magazine is given below. It suffices here to say that the magazine is so constructed that, when ejector rod 15 has pushed centrally positioned lead L₁ out of the magazine through the lower end thereof and has then withdrawn from 50 the magazine through the upper end thereof, the next succeeding lead L₂ will be moved automatically into the central or ejecting position previously occupied by lead L₁.

Now as to the ejecting means, the driving tube 55

6 thereof is mounted to rotate relative to barrel 4 but is restrained against longitudinal movement relative to the barrel by thread members 8 and 9 (see Figs. 8 and 9) which are cemented 5 or frictionally held in the upper portion of the barrel. Thread members 8 and 9 together encircle the upper cylindrical portion 10 of driving tube 6 and have inwardly extending head portions 11 which enter into neck 12 in the driving 10 tube to prevent longitudinal movement thereof. Within the upper portion 10 of the driving tube is a coil spring 13. At the lower end of spring 13 is a closely wound graduated end portion 14 which bears against neck 12. The upper and 15 large end of portion 14 just fits into portion 10 of the driving tube while the lower and small end has a sliding fit around ejecting rod 15 which it holds concentrically of the driving tube. The remainder of spring 13 has a diameter some- 20 what smaller than the large end of portion 14 so that the spring may be fully compressed within portion 10 of the driving tube. Ejector rod 15 terminates at the upper end thereof in a head 16 which has a sliding fit within portion 10 of 25 the driving tube and bears against the upper end of spring 14. Diametrically through head 16 is a hole 17 within which is rotatably mounted a T-shaped thread follower 18. The thread follower may have a square shank as shown in Fig. 4 30 or a round shank as shown in Fig. 5. The head 19 of the thread follower is flat on the sides and on the top is curved as shown in Figs. 4 and 5. The head 19 and a small portion of the shank of the thread follower extend through a longitudinal 35 slot 20 in portion 10 of the driving tube into an internal thread 21 in thread members 8 and 9. Rotating of the driving tube clockwise relative to the thread members (viewing the pencil from the tip end) results in edge 22 of slot 20 engaging the shank of thread follower 18 and moving 40 the thread follower along internal thread 21 toward the tip of the pencil. As the thread follower advances it slides along edge 22 and carries with it head 16 and ejector rod 15, resulting 45 in compression of spring 13. When the thread follower has reached the lower end 23 of thread 21 (see Fig. 9), the force of compressed spring 13 against head 16 causes the thread follower to pivot to a position in which head 19 is sub- 50 stantially parallel to the axis of the pencil and then to slide upwardly along groove 24 until head 16 reaches the end portions 25 of the thread members. Further clockwise rotation of the driving tube then causes the thread follower to pivot in 55 the recess 26 of thread member 9 and re-enter thread 21 and advance again toward the tip of the pencil. In order to permit pivoting of the thread member at the lower end (23) of the thread, a recess 27 is provided in thread member 9. 60

In order to insure that head 19 will slide smoothly across groove 24 when travelling along thread 21, and slide smoothly across thread 21 when travelling along groove 24, the head 19 is made just wide enough to have an easy sliding fit in thread 21 and groove 24 and somewhat greater than twice as long as it is wide. In practice a length approximately four times the width has been found very satisfactory. This permits 65 the head to bridge the gaps in thread 21 before the center of the head has reached the gaps. Thus the head is prevented from pivoting into groove 24. Conversely, this arrangement permits the head to bridge the gaps in groove 24 before the center of the head has reached the 70

75

gaps and prevents the head from pivoting into thread 21.

In operation, as the driving tube 6 is rotated clockwise relative to the thread members by rotating closure member 3 clockwise relative to the barrel, and thread follower 18 and ejector rod 15 advance toward the tip of the pencil, the ejector rod 15 pushes the centrally positioned lead L₁ out of the magazine toward the tip member and lead L₁, in turn, until it reaches the tip member, pushes the preceding lead L₀ through the tip member. When lead L₁ reaches the tip member it is pushed therethrough by the ejector rod until the upper end of lead L₁ and the lower end of the ejector rod reaches the lower end of the magazine. The length of the ejector rod 15 is such that when this happens the thread follower is at the lower end 23 of thread 21 and the thread follower 18, together with ejector rod 15, are then returned by spring 13 to the upper extremity of 20 their travel. This places the lower end of the ejector rod at the upper end of the magazine and permits the lead positioning means in the magazine to move the next lead L₂ into alignment with lead L₁. Further clockwise rotation 25 of the closure member then causes the ejector rod to move downwardly, pushing leads L₂ and L₁ ahead of it in the manner explained above in connection with leads L₁ and L₀. When lead L₂ has been pushed completely out of the magazine and the ejector rod has withdrawn therefrom, lead L₃ is positioned for ejection; and so on until no more leads are left in the magazine. When the magazine has been emptied it may be replaced by a full magazine by removing closure 35 member 3, tipping the pencil to cause the emptied magazine to slide out, inserting the full magazine in the pencil and replacing closure member 3. When doing this, however, it is desirable that the ejector rod be in its retracted 40 position so that it will not push the centrally positioned lead out of the magazine as the latter is inserted in the pencil.

It will be noted from the foregoing that successive leads may be fed to the tip of the pencil by rotating closure member 3 relative to the barrel in the clockwise direction. In other words, it is unnecessary to rotate the closure member in the counter-clockwise direction to permit new leads to be positioned for ejection inasmuch as retraction of the ejector rod is effected automatically by spring 13 when the thread follower has reached the lower end 23 of thread 21.

If a lead is pushed out of the tip member farther than desired, rotation of the closure member in the counter-clockwise direction will cause retraction of the ejector rod 15 and permit the lead to be pushed back into the pencil.

As will be noted from Figs. 1 and 12, the slot 20 in the driving tube is tapered, edge 28 being substantially parallel with the axis of the pencil and edge 22 being inclined therefrom. The purpose of this taper is to prevent edge 22 from being pressed against thread follower 18 as the latter moves upwardly along groove 24, notwithstanding that the driving tube is being rotated clockwise at the time. In operating the lead ejecting means of the pencil, it is quite unlikely that the operator would cease rotating closure member 3 just as the thread follower reached the lower end 23 of thread 21 and was starting to move upwardly along groove 24 under the influence of spring 13. The usual situation would be for the operator to continue rotating the closure member after the thread follower had 70 75

reached this point. Now if edge 22 were parallel with the axis of the pencil, such continued rotation of the closure member after the thread follower had started its upward movement along groove 24 would result in edge 22 engaging the thread follower and pressing it against the wall of the groove, and this might stop the movement of the thread follower along the groove. However, by inclining edge 22 away from the path of the thread follower, the closure member can be rotated to a certain extent while the thread follower moves along the groove, without edge 22 engaging the thread follower.

Figs. 1, 2 and 3 illustrate a clip which, particularly when used in connection with the construction discussed above, is very simple and easily mounted in place. Referring to Fig. 3, the clip consists of a resilient arm 29 connected, through a U bend, to an anchor arm 30. The latter tapers inwardly toward a circular enlargement 31 at its end. Referring to Figs. 1 and 2, the barrel is provided near its upper end with an outwardly pressed formation 32 conforming to the shape of anchor arm 31, and an opening 33 at the upper end of portion 32. When assembling the pencil, anchor arm 30 is inserted through opening 33 into the barrel 4 and moved to a position in which it is located in the formation 32. The thread members 8 and 9 permanently mounted on the driving tube 6 are inserted together with the driving tube into the barrel 4. The thread members 8 and 9 are cemented or otherwise rigidly mounted in the barrel 4 and they cooperate with the formation 32 against any tendency to move the clip.

An eraser 34 is fitted into the top end of the barrel above thread members 8 and 9. A cap, not shown, fitting over the top portion of the barrel may be provided if desired to enclose the eraser.

The pencil shown in Fig. 13 differs from that shown in Fig. 1 principally in that it is operated from the upper end whereas the pencil shown in Fig. 1 is operated from the tip end.

The tip member 101 is similar to the tip member 1. The closure member 103 is similar to closure member 3 except that portion 105 fits directly into the barrel 104. The spring 113, ejector rod 115, head 116 and thread follower 118 are similar to the corresponding elements of Fig. 1 and are arranged and function in same manner. The magazine M₁ functions in the same way as magazine M and may be removed through the lower end of the barrel 104 upon the removal of the closure member 103. The principal constructional differences are in the thread members 108 and 109 and the driving tube 110. The thread 121 is in the opposite direction to that of thread 21, the thread 21 being a right hand internal thread whereas thread 21 is a left hand internal thread, and recesses 126 and 127 and groove 124 are arranged to function in the same manner as the corresponding elements in thread member 9. Inwardly extending bead portions 111 function the same as portions 11, extending into neck 112 in the driving tube 110, but thread members 108 and 109 are both open at the top end. In assembly, thread members 108 and 109 are secured together and are cemented or otherwise rigidly secured to the barrel 104.

The driving tube 110 terminates at the lower end of neck 112. At its upper end the tube 110 has an enlarged portion 35 beyond and in alignment with the barrel 104. The outer diameter of the portion 35 is slightly greater than the

outer diameter of the barrel. A cap 36 fits snugly over portion 35 and covers an eraser 37 contained therein. When the cap 36 is manually rotated relative to the barrel, the tube 110 is rotated relatively to the barrel 104 and the thread members 108 and 109. The slot 120 corresponds to slot 20. However, the edge 128 is parallel to the axis of the pencil and edge 128 is inclined from the axis of the pencil. This change is necessary because in ejecting the leads tube 110 is rotated counter-clockwise relative to the thread members viewing the pencil from the tip end. A disk 38 having a central embossed central portion 39 is fixed in enlarged portion 35 to serve as an abutment for head 116 when the latter is returned to its upper position by spring 113.

In the operation of the pencil shown in Fig. 13, counter-clockwise rotation of cap 36 relative to the barrel, viewing the pencil from the tip end, results in driving tube 110 rotating counter-clockwise relative to thread members 108 and 109, and causes edge 128 to engage the thread follower 118 and advance it along thread 121 toward the tip of the pencil. As the thread follower 118 advances it carries with it head 116 and ejector rod 115 and causes spring 113 to be compressed. When the thread follower 118 reaches the lower end 123 of the thread 121 it pivots in the recess 127 and returns upwardly along groove 124 under the influence of spring 113 until head 116 abuts against central embossed portion 39 of disk 38. Further rotation of the driving tube in the same direction, causes the thread follower to pivot in recess 126 and re-enter thread 121. As ejector rod 115 moves downward, it pushes the lead or leads ahead of it toward and through the tip member 101. When the ejector rod reaches the lower end of the magazine and is returned upwardly out of the magazine under the influence of the spring 113 the next succeeding lead in the magazine is moved to central or ejecting position and is engaged and ejected by the ejector rod 115 upon subsequent downward movement thereof. As in the pencil shown in Fig. 1, rotation of the driving tube in the direction opposite from that required for ejection results in retraction of the ejector rod and permits a lead protruding from the tip member to be pushed back into the pencil. The inclination of edge 128 is for the same purpose as the inclination of edge 22, namely, to enable the automatic retraction of the ejector rod notwithstanding rotation of the driving tube during the retraction.

In this pencil, as in the pencil shown in Fig. 1, successive leads may be brought to ejecting position and ejected from the pencil without the driving tube having at any time to be rotated in the direction opposite from that required for ejection.

Referring to Fig. 18, the body of the magazine M comprises a solid body, suitably of moulded material. It is provided with a slot 40 which extends the whole length of the magazine and is of spiral form in cross section. The slot 40 is slightly wider than the diameter of the leads so that the leads, which are arranged in succession in the slot with their axes parallel to the axis of the housing, may easily be moved from one end of the spiral slot 40 to the other. The inner end of the spiral slot is at a position to hold a lead substantially coaxial with the housing and in alignment with the ejector rod 15. From this position, see Fig. 21, the slot curves smoothly into an arcuate portion which constitutes the major

portion of the slot and extends around the periphery of the magazine body. At one end of the magazine housing is an end wall 41 which closes that end of the slot save for a central 5 opening for a lead to pass therethrough. The other end of the slot is closed, save for a similar central opening, by a centrally perforated disk 42 which fits into the end of the housing.

Referring again to Fig. 21, the leads L are 10 ranged side by side in slot 40 beginning at the inner end thereof and ending a short distance from the outer end thereof. Between the outer end of the slot and the last lead is a compressed spring S. In its extended condition, the spring 15 S may be of the form shown in Fig. 19 or the form shown in Fig. 20. The spring of Fig. 19 consists of a number of flat coils whose lengths increase gradually from one end of the spring to the other. The shape of the spring as a whole is 20 flat and tapered. The spring of Fig. 20 is similar to that of Fig. 19 except that it has fewer coils and the spring as a whole is curved instead of flat. The compressed spring is arranged in the magazine with the small end of the spring against 25 the outer end of slot 40 and the large end of the spring against the last lead. The leads are thus positively urged toward the inner or central end of the slot and when the central lead is ejected from the magazine the spring pushes all the 30 remaining leads toward central position a distance equal to the diameter of a lead and locates in the central position the lead which previously was next to the lead ejected from the magazine. When this newly located central lead is ejected 35 from the magazine the process is repeated, and so on, until, as shown in Fig. 22, the magazine is only about half full or until, as shown in Fig. 23, only one lead remains in the magazine.

The curvature in the spring of Fig. 20 facilitates the expansion of the spring around curved 40 slot 40. If the spring is flat as in Fig. 19, it is necessary to have more coils in order to insure expansion of the spring completely around the curved slot 40. The end of the wire at the large 45 end of spring S is bent, as indicated by reference numeral 43 in Figs. 19 and 20, in order to insure that the end of the wire will bear against the last lead and not become wedged between the leads and the wall of the slot. Bend 43 extends beyond 50 the adjacent coil so as to avoid becoming tangled therewith when the spring is compressed.

When the magazine is in either one of the pencils described above, the lead at the inner or central end of slot 40 is substantially coaxial with 55 respect to the pencil and is ejected from the magazine by the ejector rod 15 or 115, and when the ejector rod has then been retracted from the magazine by the return spring 13 or 113 spring S moves the next succeeding lead to central or 60 ejecting position.

The magazine illustrated in Fig. 24 is similar to that of Fig. 18 except that the slot 44 for the leads is provided at its outer end with a longitudinal enlargement 45 and adjacent the ends of the housing with spiral enlargements 46 and 47. The purpose of these enlargements is to provide a track for a coil spring 48 which, when the magazine is full of leads, is compressed in portion 45 and which, when the central lead is ejected from 70 the magazine, expands along portions 46 and 47 and bears against the extremities of the last lead to push the leads toward central position. The spring 48 is somewhat greater in diameter than the width of slot 44 between the enlargements 46 and 47 so that it will be prevented from expand-

ing out of portions 45, 46 or 47 into the remainder of the slot. Fig. 26 shows the magazine with a full supply of leads L with spring 48 bearing against the last lead. Fig. 27 shows the condition of the magazine after about half the 5 leads have been ejected with spring 48 urging the remainder toward central position. Fig. 28 shows the magazine after the last lead has been pushed into central position by spring 48. Centrally perforated disks similar to disk 42 are 10 placed in both ends of the magazine to retain the leads and spring therein. The magazine shown in Fig. 24 operates in the pencil shown in Fig. 1 or Fig. 13 in the same manner as the magazine of Fig. 18, that is, when the ejector rod 15 or 115 has ejected the centrally positioned lead from the magazine and has automatically retracted, the spring 48 pushes the next succeeding lead into central position.

It is immaterial which end of either magazine 20 is inserted in the pencil first as the springs S or 48 function equally well in both relations. When the last lead has been ejected from the magazine it is intended that the empty magazine be withdrawn and discarded and a full new magazine inserted in the pencil. In order to notify the user 25 when the magazine is almost empty, it is proposed that the last lead or two shall have a distinguishing appearance such as being coated or tipped with a material of different color. 30

As shown in Fig. 8 I prefer to provide near the upper end of thread 21 a recess terminating in a shoulder 49 so arranged that if it is attempted to retract the thread follower 18 along the thread 21 completely to the upper end thereof, the thread follower 18 will be forced against the shoulder by spring 13 and blocked against further upward travel. The purpose of this shoulder is to prevent the ejector rod 15 from being manually retracted completely out of the magazine. 40 In the absence of the shoulder 49, it would be possible to advance the upper end of lead L₁ (for example) to a point slightly above the lower end of lead L₂ and then manually retract the ejector rod completely out of the magazine, permitting the leads other than lead L₁ in the magazine to be tilted (by spring S or 48) to a position in which the upper end of lead L₂ is in central position and the lower end of lead L₂ is held out of central position by the upper end of lead L₁. Subsequent downward movement of the ejector rod would then jam lead L₂ against the lower end of the magazine and necessitate removal of the magazine from the pencil to permit withdrawal of lead L₁ from its obstructing position in the magazine. Shoulder 49, however, by preventing manual retraction of the ejector rod completely out of the magazine, obviates this possibility of jamming the pencil. Shoulder 149 in thread 121 (Fig. 15) is for the same purpose as 50 shoulder 49. 60

Although the invention has been described in connection with the specific details of preferred embodiments thereof, it must be understood that such details are not intended to be limitative of 65 the invention except insofar as included in the accompanying claims.

Having thus described my invention, I declare that what I intend to claim is:

1. An automatic pencil comprising a barrel, 70 a tip member at one end of the barrel having an axial opening for the discharge of lead, a threaded member in the barrel, a lead magazine in said barrel below said threaded member and having axial openings, and a longitudinal groove 75

- terminating adjacent the axis of the magazine so as to locate a lead in co-axial relation to said magazine and openings, a thread follower adapted to cooperate with said threaded member, a rod 5 located in alignment with the axis of the magazine and operatively connected to said thread follower so as to move axially therewith, means for manually rotating said follower relatively to the threaded member to effect longitudinal movement of the follower and lead ejecting rod, a 10 spring tending to retract the thread follower and rod, said threaded member being provided with a longitudinal groove adapted to receive the follower at the end of an expelling movement to permit the spring to retract the rod and follower.
2. An automatic pencil comprising a barrel, a tip member at one end of the barrel having an axial opening for the discharge of lead, a threaded member in the barrel, a lead magazine in said 15 barrel and provided with means for feeding leads into alignment with said axial opening, a thread follower adapted to cooperate with said threaded member, a rod located in alignment with the axis of the magazine and operatively connected 20 to said thread follower so as to move axially therewith for ejecting axially aligned leads through said axial opening, a sleeve having a longitudinal slot to effect manual rotation of the follower relative to the threaded member to cause longitudinal movement of the follower and lead 25 ejecting rod, a spring tending to retract the thread follower, said threaded member being provided with a longitudinal groove communicating with the thread of said threaded member for receiving the follower at the end of an expelling movement to permit the spring to retract the rod and follower.
3. An automatic pencil comprising a barrel, a tip member rotatably mounted at one end of the 30 barrel having an axial opening for the discharge of lead, an internally threaded member in the barrel, a lead magazine in said barrel between said tip and said threaded member and adapted to feed leads into alignment with said axial opening, a thread follower adapted to cooperate with 35 said threaded member, a rod located in alignment with the axis of the magazine and operatively connected to said thread follower so as to move axially therewith for moving leads through said axial opening, a sleeve rigid with the tip member having a longitudinal slot to effect 40 manual rotation of the follower relative to the threaded member to cause longitudinal movement of the follower and lead ejecting rod, a spring tending to retract the thread follower, said threaded member being provided with a longitudinal groove provided with terminal extensions 45 communicating with the ends of said thread for directing the follower into said groove at the end of an expelling movement to permit the spring to retract the rod and follower and for redirecting said follower from the groove into said thread upon retraction of the rod and follower by said spring.
4. An automatic pencil comprising a barrel, a tip member at one end of the barrel having an axial opening for the discharge of lead, a threaded member in the barrel, a lead magazine adapted to feed leads into alignment with said axial opening, a thread follower adapted to cooperate with 50 said threaded member, a rod operatively connected to said thread follower so as to move axially therewith for moving leads through said axial opening, a sleeve having a longitudinal slot to effect manual rotation of the follower relative to the threaded member to cause longitudinal movement of the follower and lead ejecting rod, a member carried by said sleeve beyond the upper end of the barrel whereby the sleeve may be rotated manually, a spring tending to retract the thread follower, said threaded member being provided with a longitudinal groove provided with a terminal extension co-acting with the threads of said threaded member for directing the follower into said groove at the end of an expelling movement to permit the spring to retract the rod and follower.
5. A magazine for a mechanical lead pencil adapted to be inserted into and removed from the pencil comprising a body portion having a slot adapted to contain a series of leads, the lead at one end of the slot being in position for ejection, and resilient means adapted positively to move the leads through the slot successively to said ejection position.
6. A magazine for a mechanical lead pencil adapted to be inserted into and removed from the pencil and consisting of a housing having a longitudinal slot of generally spiral cross-section adapted to contain a series of leads, and resilient means adapted positively to move the leads through the slot towards one end of the slot.
7. A magazine for a mechanical lead pencil adapted to be inserted into and removed from the pencil comprising a housing having a slot of generally spiral shape adapted to contain a series of leads, a coil spring compressed between the outer end of the slot and the last lead in the series and consisting of a number of flat coils for moving the leads through the slot to lead ejecting position.
8. A magazine for a mechanical lead pencil adapted to be inserted into and removed from the pencil and comprising a housing having a slot of generally spiral shape adapted to contain a series of leads, and a coil spring compressed between the outer end of the slot and the last lead in the series to move the leads to lead ejecting position, said spring consisting of a number of flat coils whose lengths increase progressively from one end of the spring to the other, the large end of the spring bearing against the last lead and the small end of the spring bearing against the outer end of the slot.
9. A magazine for a mechanical lead pencil adapted to be inserted into and removed from the pencil and comprising a housing having a longitudinal slot of generally spiral cross-section adapted to contain a series of leads, and a spring expandable within the slot to move the leads through the slot to ejecting position therein, said spring being a coil spring compressed between the outer end of the slot and the last lead in the series and consisting of a number of flat coils whose lengths increase progressively from one end of the spring to the other, the large end of the spring bearing against the last lead and the small end of the spring bearing against the outer end of the slot, and the spring as a whole, particularly near the large end thereof, being curved to assist it in expanding around the spiral slot.
10. A magazine for a mechanical lead pencil adapted to be inserted into and removed from the pencil and consisting of a housing having a slot of generally spiral shape adapted to contain a series of leads, said slot having enlarged portions along its outer end and along its spiral ends, and a spring expandable within the slot to move the leads through the slot successively to ejecting position therein, said spring being a coil spring

compressed between the outer end of the slot and the last lead in the series, said coil spring being greater in diameter than the width of the slot and adapted to expand along said enlarged portion at 5 the outer end of the slot and along said enlarged portions at each end of the magazine.

11. A magazine for a mechanical lead pencil adapted to be inserted into and removed from the pencil and comprising a housing provided with a 10 slot of generally spiral shape extending longitudinally therethrough and adapted to contain a series of leads, and resilient means adapted positively to move the leads through the slot to ejecting position therein, the inner end of the slot being 15 located to hold a lead substantially coaxial with respect to the exterior of the housing.

12. In combination a mechanical lead pencil, a magazine adapted to be inserted into and to be removed from the pencil and consisting of a housing 20 having a slot, leads in said magazine, and means adapted positively to move the leads through the slot to ejecting position therein, at least one of the latter leads in the succession being distinctly colored to indicate the amount 25 of lead remaining in the magazine.

13. A pencil comprising a barrel provided with a tip, said barrel having an internal thread, a lead feeding plunger within the barrel, a spring in the barrel compressible by the plunger as the 30 latter is operated to feed a lead through said tip, a follower pivotally connected to said plunger and cooperable with the threads of said barrel for advancing the plunger within the latter, and a longitudinal groove within said barrel traversing the 35 convolutions of said thread and provided with terminal portions communicating with the ends of said thread, the lower of said portions being arranged to swing said follower pivotally at the end of the lead feeding operation for directing said 40 follower from the thread into said groove for retraction of the follower and plunger by said spring, said other terminal portion of the groove

being adapted to direct the follower from the groove into position for co-action with said thread upon retraction of the plunger by said spring.

14. A mechanical pencil comprising a barrel, a lead magazine therein provided with a lead feeding passage, means in the magazine for feeding successive leads laterally into said passage, an interiorly threaded member in the barrel above the magazine provided with a longitudinal groove for 10 directing a follower from the lower end to the upper end of the thread of said member, a rotatable sleeve within said threaded member provided with a longitudinal slot and with an annular inwardly directed spring seat, said seat comprising an exterior cavity constituting means rotatably securing the sleeve to the threaded member for restraining relative axial movement of the sleeve within the barrel, a lead advancing rod in said sleeve aligned with the passage of said magazine 20 and provided with a thread follower projecting through the slot of said sleeve for cooperation alternately with said thread and groove whereby upon rotation of the sleeve the follower is moved by the thread longitudinally of the barrel to cause 25 the rod to advance a lead downwardly through said magazine passage, a spring in said sleeve having one end in contact with said follower and the other end comprising a plurality of convolutions of successively reduced diameters constituting 30 an abutment adapted to seat on said spring seat of the sleeve and providing a centralized guiding passage for said rod, said spring being compressible by said follower during the lead advancing movement thereof whereby upon the movement of said follower from the thread into 35 said groove said follower is restored by said spring to the upper end of the thread and said rod is retracted from the magazine to enable another lead to be fed from the magazine into said magazine 40 passage.
